PATENTED DEC. 5, 1905.

C. W. VAN WYE.

AUTOMATIC DRAFT COUPLING FOR AGRICULTURAL MACHINERY.

APPLICATION FILED MAY 5, 1905.

UNITED STATES PATENT OFFICE.

CHARLES W. VAN WYE, OF FREEPORT, KANSAS.

AUTOMATIC DRAFT-COUPING FOR AGRICULTURAL MACHINERY.

No. 806,216.

Specification of Letters Patent.

Patented Dec. 5, 1905.

Application filed May 5, 1905. Serial No. 258,999.

To all whom it may concern:

Be it known that I, CHARLES W. VAN WYE, a citizen of the United States, residing at Freeport, in the county of Harper and State of 5 Kansas, have invented certain new and useful Improvements in Automatic Draft-Couplers for Agricultural Machinery, of which the following is a specification.

This invention relates to a draft-coupler for 10 agricultural machinery, and has for its object to produce a device of this character which shall be extremely simple in construction, which will be positive in operation, and which can be very easily operated.

15 Reference is to be had to the accompanying drawings, in which—

Figure 1 is a plan view of the device in a locked position with the cover removed. Fig. 2 is a similar view showing it in an unlocked 20 position. Fig. 3 is a perspective view.

Corresponding and like parts are referred to in the following description and indicated in all the views of the drawings by the same reference characters.

25 The draw-head 1 is provided, as usual, with a mouth 2 and throat 3 and has at the opposite end a tongue 4 for the purpose of attaching it to a car. A knuckle 5 is pivoted at one side of the throat 3 and a tripping-lever 6 at the opposite side. When in the locked position, one arm 7 of the knuckle 5 extends directly across the throat 3, while the other arm 8 extends back into the draw-head and engages a spring 9. The tripping-lever 6 has 35 one arm 10, which passes out through an opening 11 in the side of the draw-head and lies normally along said side, while the other arm 12 makes a locking engagement with the arm 7 of the knuckle 5. The spring 9 is held in 40 position in the rear of the draw-head by lugs 13 projecting therefrom and has its respective ends operating upon the knuckle and tripping-lever. As seen in the drawings, one end of the spring bears upon the shoulder 14 of the 45 tripping-lever 6, while the other end is bent back and forth within the draw-head and bears against the arm 8 of the knuckle. Lugs 15 and 16 project inward from a face of the draw-head to limit the movement of the 50 knuckle and tripping-lever. The coupling-link 17 used in connection with the aforescribed draw-head is of the usual construction and consists, essentially, of a yoke having a pin 18, connecting the ends of its projecting arms.

The operation of the device is as follows:

When the arm 10 of the tripping-lever 6 is pulled outward, which may be accomplished, if desired, by means of a wire or small rope fastened to an opening 19 in the end thereof, the other arm 12 is thrown out of engagement with the arm 7 of the knuckle 5, and said arm 7 is swung around under the casing, and the other arm 8 of the knuckle 5 is thrown across the throat 3. Now if the pin 18 of the coupling-link 17 is forced into the throat 3 it will engage and force inward the arm 8 of the knuckle, and thus swing the arm 7 back across the throat. In so doing the arm 7 will first engage the arm 12 of the tripping-lever and force that lever around until it has passed it, when the spring 9 will cause said lever 6 to spring back into position and prevent the coupling-link 17 from forcing the knuckle around so as to release it. By reference to the 75 drawings it will be observed that any outward pull of the coupling-link forces the arms 7 and 12 into engagement with each other and tends to turn the tripping-lever 6 about its pivot, which it is prevented from doing by 80 the fact that its arm 10 lies against and is engaged by the side of the draw-head. When in a locked position, the engaging faces of the arms 7 and 12 are intended to be approximately in the circumference of a circle described about the pivot of the tripping-lever 6 as a center. This has the advantage that when the lever 6 is turned so as to release the coupling-link 17 there will be no movement of the arm 7 until the locking connection is 85 completely broken. On this account a very slight pull will suffice to unlock the coupler.

It will be perfectly obvious that if desirable a coil-spring may be placed around the attaching-tongue 4 to eliminate the sudden jerks 95 and jars caused in starting and stopping.

From the foregoing description it will be readily understood that I have invented a draft-coupler for agricultural machinery which has manifest advantages over those now 100 in use.

Having thus described the invention, what is claimed as new is—

1. In a draft-coupler for agricultural machinery, the combination of a draw-head having a mouth and throat therein, a knuckle, one arm of which normally projects across the throat and the other arm of which is engaged by a spring, and a spring-actuated tripping-lever, one arm of which passes out and lies normally against the outside of the draw-head. 105
2. In a draft-coupler for agricultural ma-

achinery, the combination of a draw-head having a mouth and throat therein, a knuckle pivoted upon one side of the throat, one arm of which normally projects across the throat and 5 the other arm of which is engaged by a spring, a spring-actuated tripping-lever pivoted upon the other side of the throat, and a spring fastened in the rear of the draw-head, the respective ends of which are bent to engage with the knuckle and tripping-lever.

10 3. In a draft-coupler for agricultural machinery, the combination of a draw-head having a mouth and throat therein, a knuckle pivoted upon one side of the throat, one arm of 15 which normally projects across the throat and

the other arm of which is engaged by a spring, a spring-actuated tripping-lever pivoted upon the other side of the throat, one arm of which passes out and lies normally against the outside of the draw-head, and a spring fastened 20 in the rear of the draw-head, the respective ends of which are bent to engage with the knuckle and tripping-lever.

In testimony whereof I affix my signature in presence of two witnesses.

CHARLES W. VAN WYE. [L. S.]

Witnesses:

J. A. HAZLE,
J. M. FERGUSON.
